UNITED STATES PATENT OFFICE.

EDGAR C. MOLBY, OF BROOKLYN, NEW YORK, ASSIGNOR TO IRON PRODUCTS CORPORATION, OF NEW YORK, N. Y., A CORPORATION OF DELAWARE.

DESIGN FOR A COMBINATION HEATER AND OPEN FIRE GRATE.

60,294.

Specification for Design.

Patented Jan. 24, 1922.

Application filed May 9, 1921. Serial No. 468,179. Term of patent 14 years.

To all whom it may concern:

Be it known that I, EDGAR C. MOLBY, a citizen of the United States, residing in the borough of Brooklyn, city of New York, county of Kings, and State of New York, have invented a new, original, and ornamental Design for a Combination Heater and Open Fire Grate, of which the following is a specification, reference being had to the accompanying drawing, forming a part hereof.

The single figure of the drawing is a perspective view of a heater embodying my new design of a heater, which also operates as an open fire grate.

I claim:

The ornamental design for a combination heater and open fire grate as shown.

EDGAR C. MOLBY.
